UNITED STATES PATENT OFFICE.

JOHN A. SPENCER, OF REVERE, MASSACHUSETTS, ASSIGNOR TO SPENCER THERMO-STAT COMPANY, OF CAMBRIDGE, MASSACHUSETTS, A CORPORATION OF MASSACHUSETTS.

GAS JET.

Application filed October 23, 1924. Serial No. 745,411.

The use of gas lights of the usual and well-known type employing an unprotected flame in open places which are exposed to frequent drafts is particularly dangerous because the flame is often accidentally extinguished and the gas which escapes thereafter frequently causes serious injury to life and property. This invention is concerned with safety devices for such lights and objects of the invention are to eliminate the above danger in the ordinary use of illuminating gas; and to provide a thermostatically controlled device operable automatically at different predetermined temperatures for controlling the flow of fluid from one place to another.

The invention is shown by way of illustration in the accompanying drawings in which:—

Fig. 1 is an elevation of a gas fixture embodying the present invention;

Fig. 2 is a vertical section of the gas jet showing the thermostatic disk in cold position;

Fig. 3 is a vertical section of the gas jet showing the thermostatic disk in heated position; and

Fig. 4 is a plan view of the thermostatic disk.

In the illustrated embodiment of the invention the ordinary gas lighting fixture A comprises a tube 1 suitably attached to a supply pipe in the wall or support 2 and the flow of gas to the tube 1 is controlled by the usual valve 3. Attached to the outer end of the tube 1 is a gas jet B through which gas passes to the tip 4 where it is ignited.

In accordance with the invention the gas jet comprises a sheet metal casing 5 constructed in two sections, a substantially frusto-conical upper section 6 the outer end of which frictionally holds the tip 4, and the lower cup-shaped section 7, over which the section 6 is crimped or flanged securely to hold the sections together. Integral with the lower section 7 and extending outwardly therefrom in axial alignment with the tip 4 is an internally threaded projection 8 which is threaded over the usual upstanding tube on the tube 1. Formed in the projection 8 is an opening 9 about which is a valve seat

with which a valve 10 cooperates to control the flow of gas through the casing.

The valve 10 is seated and unseated at different predetermined temperatures so that in the event of the flame being accidentally extinguished the flow to the tip 4 is automatically shut off. Accordingly a thermostatic disk 11 having apertures 12 through which gas passes when the valve is opened is supported at its periphery by a shoulder 13 formed in the casing section 7, and is connected by a stem 13 to the valve 10.

The disk 11 is preferably bi-metallic, being formed of two component disks welded together, the materials such as iron and brass of the component disks having different coefficients of expansion. The disk 11 is normally cupped (as by swaging) in such direction that the component part having the higher coefficient of expansion is on the concave side. Consequently when the disk is heated it tends to snap through to reverse position. The materials and thicknesses of the component parts and the degree of curvature are so chosen that the disk will snap through when heated to the desired temperature (e. g. 120° F.) and will snap back at a lower temperature (e. g. 100° F.). Suitable materials are sheet brass and nickel sheet having thicknesses of .005 and .005 inch respectively and suitable cupping for a disk $\frac{3}{4}$ inch in diameter is .020 inch.

It should be understood that the present invention is not limited to any particular combination of materials having different thermal coefficients of expansion but is intended to embrace in its scope any combination of materials having dissimilar thermal coefficients of expansion sufficient to cause the characteristic reversal of curvature. Furthermore, the two materials comprising the composite thermostatic sheet may be secured together in any desired manner by riveting, soldering, brazing or otherwise although it is preferred to unite the materials comprising the sheet by welding or similar means to secure a substantially indivisible sheet.

From the foregoing it will be evident that in one aspect the invention involves a ther-

mostatic device characterized by portions arranged to react upon each other with change of temperature to set up stresses the magnitude of which changes upon change of temperature, at least one of the portions being formed of different metals or other components having different coefficients of expansion, the device reaching a condition of instability at a predetermined temperature by virtue of the arrangement of said portions and as a result of the differential expansion of the components due to change of temperature, whereupon said stresses become effective to change abruptly the relative position of said portions.

As shown in Fig. 2 the disk assumes an upwardly cupped shape in its cold position, so that normally the valve 10 is closed, but as soon as the temperature increases sufficiently it abruptly snaps to the downwardly cupped position shown in Fig. 3 thereby to open the valve. The change of shape in the disk is decidedly abrupt whether in one direction or the other, so that the valve is seated or unseated according to the temperature thereof to open and close the passage of gas through the casing. Such disk is constructed in such a manner that changes in shape occur with considerable force so that positive opening and closing of the passage is insured and owing to its great inherent resiliency and rugged construction the disk will operate indefinitely in a reliable and efficient manner. It will be evident that the valve 3 may be dispensed with entirely or if desired turned on at all times because the thermostatic disk 11 automatically shuts off the gas when it is not required.

In order to open the valve 10 a lighted match or taper is held adjacent the casing section 7 in the vicinity of the disk 11 in order to raise the temperature of the latter sufficiently for it to snap downwardly (Fig. 3) which movement operates to unseat the valve thereby opening the passage of gas through the casing 5 and perforations 12 to the tip 4 where it is lighted. After the gas is ignited the heat from the flame maintains the valve open. Should the flame accidentally be extinguished or the supply of gas turned off by the valve 3, the thermostatic disk will be cooled sufficiently to snap to its normal position (Fig. 2) and seat the valve 10.

An outstanding characteristic of the invention consists in that the passage of fluid through a conduit is controlled by a thermostatic device which is operable automatically at different predetermined temperatures to open and close the passage. Preferably the passage is normally closed to prevent waste of fluid until the temperature rises to a predetermined degree when it is instantaneously opened. A unique charac-

teristic of the thermostatic device consists in that it snaps abruptly and forcibly to its hot position at a predetermined temperature and likewise snaps abruptly and forcibly to its cold position at a lower predetermined temperature; and a gas jet having such a thermostatic device is comprehended in the present invention.

I claim:

1. A gas jet comprising a casing having a cylindrical passage with an outwardly flared wall portion, intermediate its ends, a thermostatic disk in said outwardly flared portion, said disk being perforated to permit the flow of gas, and being operatively connected with a valve in the cylindrical passage to control the flow of gas through the casing.

2. A gas jet comprising a casing, a valve in said casing for controlling the passage of gas therethrough, and a thermostatic disk within said casing connected to said valve and constructed abruptly to open the latter at a predetermined temperature and close at a predetermined lower temperature.

3. A gas jet comprising a casing, a valve in said casing for controlling the passage of gas therethrough, and a perforated thermostatic member within said casing connected to said valve for opening and closing the latter at different predetermined temperatures.

4. A gas jet comprising a casing, a valve for controlling the passage of gas therethrough, and a perforated thermostatic disk connected to said valve and constructed to open the latter at a predetermined temperature, the gas flowing through the perforated disk.

5. A gas jet comprising a casing, a valve in said casing for controlling the passage of gas therethrough, a perforated thermostatic disk arranged in said casing transversely to the axis thereof, and a connection between said disk and valve, the disk being constructed to open and close said valve at different predetermined temperatures.

6. A gas jet comprising a casing, a valve in said casing for controlling the passage of gas therethrough, a perforated thermostatic disk arranged in said casing transversely to the axis thereof in advance of said valve, and a connection between said disk and valve, the disk being constructed normally to hold said valve in a closed position and to open said valve when the temperature of the former reaches a predetermined temperature.

7. An article of manufacture comprising a casing having a fluid passage therethrough, a valve controlling said passage, and a perforated thermostatic disk within said casing connected to said valve and constructed to open the latter at a predetermined lower temperature.

mined relatively high temperature and close the latter at a predetermined relatively low temperature.

8. In thermostatic control apparatus, the combination of a casing having a valve seat, a valve fitting said seat, and a disk thermostat in said casing constructed and arranged

to snap the valve into or out of its seat when subjected to predetermined temperature changes, said disk being apertured to permit fluid to pass therethrough. 10

Signed by me at Cambridge, Massachusetts, this second day of October, 1924.

JOHN A. SPENCER.
